UNITED STATES PATENT OFFICE

WILLIAM E. KEENAN, OF CLARENCE, PENNSYLVANIA

SCRAPER FOR FLOWING WELLS

Application filed December 5, 1929. Serial No. 411,937.

This invention relates to means for scraping paraffine from the interior of a well casing in flowing wells. In many of the oil fields, especially, for instance, in the Texas oil fields, paraffine becomes very troublesome. In many of the big flowing wells as well as in the gas lift and pumping wells, paraffine collects on the inside of the casing or tubing and stops the flow of oil and gas in a very few days.

The general object of the present invention is to provide a scraping tool adapted to be mounted on a connection of the drill stem or auger stem or otherwise which is so formed that as it is lowered downward inside of the casing or tubing, it will cut the paraffine loose without, however, in any way obstructing the free flow of the oil or gas so that the paraffine may be "flowed" out with the gas or air, whichever is being used to flow the well.

A further object is to provide a tool of this character which has the form of a longitudinally twisted scraper or screw, the edges of the screw constituting cutting edges, the lower end of the tool being so formed that it will cut straight downward through the paraffine collected on the wall of the casing and will hold the scraper straight while it is cutting the paraffine.

A further object is to provide a scraper which is reversely twisted as regards its upper and lower portions so that when used in high pressure wells, it will prevent putting too much twist in the drill cable.

If twist only in one direction were used, under these circumstances, the high pressure would cause the scraper to spin, but by using a reverse twist or a double twist, the pressure against the screw is balanced.

Other objects will appear in the course of the following description.

My invention is illustrated in the accompanying drawings, wherein:—

Figure 1 is a longitudinal sectional view through a well casing showing my paraffine remover applied thereto;

Figure 2 is an enlarged view of the paraffine remover by itself and

Figure 3 is a section on the line 3—3 of Figure 2.

Referring to the drawings, A designates a well casing with the usual coupling B. C designates the auger or drilling stem to which my tool is attached and which has the usual pin joint to the drill jars D. These drill jars at their upper ends are connected to the rope socket E. The lower end of the drill stem C is provided with the usual screw-threaded socket. All of these parts are old and well known.

My improved paraffine cutting tool consists of a scraper 10 which is twisted in its length and has a width approximately that of the interior of the casing. This scraping blade may have an overall length of between six and seven feet. At the lower end, the scraper blade 10 is formed to provide a portion 11 having a longitudinal straight edge 12 approximately eight inches long in actual practice, though it may have any desired length. The lower end of the blade is beveled to form a cutting edge 13. This portion 11 has a width approximately that of the interior of the casing so that as the scraper is lowered in the well, this straight edge 12 will cut into the paraffine lining the casing and this will hold the scraper from rotation while the paraffine is being scraped off the casing and blade. Though I do not wish to be limited to this, the blade will preferably have reverse twists, that is, the upper portion of the blade may have a right hand twist and the lower portion of the blade a left hand twist. The edges of the blade are sharply beveled so as to cut the paraffine from the inner face of the casing.

The upper end of the blade is square at 14 and above this is provided the collar 15 having the usual screw-threaded pins 16 whereby it may be connected into the socket at the lower end of the drill stem. While in wells having low pressure, a scraper having a twist all in one direction may be used, yet I do not wish to be limited to this as in high pressure wells, it is desirable to provide a reversely twisted screw so that the pressure of gas, oil or air which is being used to cause the well to flow will not tend, by its action

upon the twisted blade, to turn the blade around axially and thus put too much twist on the drilling cable. By using the double twist, however, the pressure is equalized.

5 Preferably there is a little more twist on one portion of the scraper than on the other so as to keep a slight twist on the cable.

In the use of this device, the sharp edges of the scraper cut the paraffine loose and the 10 flow of gas and oil flows it out of the casing. The elongated lower portion 11 on the lower end of the scraper enters the paraffine on the walls of the inner side of the casing and this tends to keep the scraper from turning, thus causing the scraper to remove the 15 paraffine on the inside of the casing and does not permit the scraper to rotate or cut what may be termed screw-threads in this paraffine without affecting the paraffine.

20 With this paraffine remover I have kept wells flowing for nearly a year steadily. If a drilling bit had been used to remove the paraffine, it would form a ball of paraffine and kill the flow of oil and gas. My device 25 in no way impedes the flow of oil or gas, while at the same time fully cleans the walls of the well of paraffine.

While I have illustrated certain details of 30 construction and arrangements of parts, it will be understood that I do not wish to be limited to this except in so far as limited by the claims.

I claim:—

35 1. A paraffine remover of the character described, comprising a blade having portions twisted in reverse directions, the blade having a width approximately equal to the interior diameter of a well casing with which it is used and having cutting edges, the lower end 40 of the said blade having a transversely flat, longitudinally straight portion extending diametrically through the longitudinal axis of the twisted blade and having cutting edges adapted to form longitudinal cuts in the paraffine collected on the wall of the casing, this straight portion having a cutting edge at 45 its lower end.

2. Means for removing paraffine from the 50 interior face of a well casing including a drill jar, having means whereby it may be supported from a cable, a drill stem engaged with the drill jar and a steeply twisted blade formed at its upper end for engagement with the drill stem, the blade having a width approximately equal to the interior diameter of the well casing with which it is to be used and having cutting edges and the lower end 55 of the blade having a transversely flat, longitudinally straight portion extending diametrically through the axis of the twisted blade and having longitudinally straight edges adapted to form longitudinal cuts in the paraffine lining the wall of the casing to thereby hold the blade from rotation.

60 65 3. Means for removing paraffine from the

interior face of a well casing including a drill jar, having means whereby it may be supported from a cable, a drill stem engaged with the drill jar and a steeply twisted blade formed at its upper end for engagement with the drill stem, the blade having a width approximately equal to the interior diameter of the well casing with which it is to be used and having cutting edges and the lower end of the blade having a transversely flat, longitudinally straight portion extending diametrically through the axis of the blade and having opposed longitudinally straight cutting edges adapted to form longitudinal cuts in the paraffine lining the wall of the casing to thereby hold the blade from rotation, the blade being twisted in reverse directions.

In testimony whereof I hereunto affix my signature.
